Marshall Lawrence

UNITED STATES PATENT OFFICE.

ROBERT EXLEY, OF PHILADELPHIA, PENNSYLVANIA.

ELECTRICAL STOP-MOTION FOR STEAM-ENGINES.

SPECIFICATION forming part of Letters Patent No. 378,668, dated February 28, 1888.

Application filed October 15, 1887. Serial No. 252,433. (No model.)

To all whom it may concern:

Be it known that I, ROBERT EXLEY, a citizen of the United States, residing at Philadelphia, in the county of Philadelphia and State 5 of Pennsylvania, have invented certain new and useful Improvements in Electrical Stop-Motions for Steam-Engines; and I do hereby declare the following to be a full, clear, and exact description of the invention, such as will 10 enable others skilled in the art to which it appertains to make and use the same.

My invention relates to a device for stopping steam - engines by means of electricity; and it consists in a valve-rod having a divided 15 end bearing kept together by a stepped arm, which latter is within range of a spring-bolt, and is tripped when the spring - bolt is released by the armature of a charged magnet, so that the weight of the valve-rod will cause 20 the said end bearing to part and leave the pin of the valve mechanism, thus stopping the engine.

In the accompanying drawings, Figure 1 is a side elevation of a cylinder and valve-gear 25 of a "Corliss" engine provided with my invention. Fig. 2 is an enlarged view of the valve-operating center lever and eccentric-rod, both provided with my invention and shown in operation. Fig. 3 is a transverse section in 30 the line $x-x$ of Fig. 2. Fig. 4 is a diagram of a mill or establishment having switches, a battery, and an engine with my stop-motion.

The letter A in the drawings represents a cylinder of a Corliss steam-engine; B, eccentric-rod; C, center lever; D D', steam-valves; 35 E E', exhaust-valves, and F electric mechanism.

The steam - valves D D' are provided with lever-arms d and connecting-rods d', by means 40 of which they are connected with the center lever, C. In a similar way the exhaust-valves E E' are provided with lever-arms e and connecting-rods e', whereby they are connected with the center lever, C, as shown. The connecting-rods d' and e' are attached to the center lever, C, by means of ordinary wrist-pins, 45 c, fastened to said center lever by means of nuts c', as shown. The stud c'', around which the center lever oscillates, is provided with a 50 box, G, which is firmly secured thereto by means of a nut, g. This box G contains the electric stop mechanism F, consisting of an

electric magnet, H, check-bolt h, armature h', and spring-bolt I. The magnet H is of ordinary construction, and the armature h' is in 55 range of a lug, h², upon the bolt h, so that it will push it along when attracted by the magnet. The bolt h is tapered, and its small end enters the spring-bolt I, as indicated by dotted lines in Fig. 1, the socket - hole i, which 60 receives the end portion of the bolt h, being shown in dotted lines in Fig. 2. The bolt h is prevented from leaving its bearings by a lug, h³, which strikes the wall of the box G after it is moved entirely from the spring-bolt I. By 65 tapering the bolt h, I greatly reduce the friction in its bearings, thus making it easier for the armature h' to withdraw it from the spring-bolt I. The spring-bolt moves in guide-walls 7c g' g² of the box G, and it has a cylindrical end portion, i', which slides in a bridge portion, g³, of the box, between which bridge portion and the end surface of the spring - bolt I a spring, i², is provided, which expedites the outward motion of the spring-bolt I when the 75 check-bolt h is withdrawn. The spring-bolt I is prevented from leaving its bearings in the box G by a check, g⁴, bridging the guide-walls g' g² and touching the bottom surface of a depression, i³, of said spring - bolt, the upper 8c shoulder, i', of the said depression bearing against the check g⁴.

Below the box G the eccentric-rod B is provided with a stepped lever, b, pivoted at b' to it and holding in place by means of a shoulder, b², the end portion, j, of the upper half-bearing, J, of the wrist-pin c' of the center lever, C, and eccentric-rod B. This upper half-bearing, J, is pivoted at j' to the eccentric-rod B, in which is formed the lower half-bearing, 85 b⁶, of the said wrist-pin, and thus they jointly inclose the wrist-pin and firmly connect the center lever, C, with the eccentric-rod B.

A spring, b³, hung between the lower portion, b⁴, of the lever b, and a suitable lug, b⁵, 95 on the eccentric-rod B, holds the lever b with its shoulder b² upon the end portion, j, and thus prevents accidental parting of the upper half-bearing, J, from the eccentric-rod B. The eccentric-rod moves in a slotted guide-stand, K, 100 the purpose of which will be presently shown.

The coils h⁴ of the magnet H are, by means of circuit-wires h⁵ h⁶ of an open circuit, connected to a battery, h⁷, Fig. 4, and a number

of switches, h^8 , by means of branch wires $h^9 h^{10}$. The battery will be placed in a convenient and safe part of the building, and the switches will be placed where accidents are liable to happen—that is, near dangerous and exposed gearing or belting.

When a person is accidentally caught in the machinery of a mill or shop supplied with my invention, he or a friend near by will push a button of the nearest switch h^8 , thereby charging the magnet H and attracting its armature, which, by pulling the bolt h away from the socket-hole i , allows the spring-bolt I to slide down within range of the lever b . The lever b in its forward motion strikes the spring-bolt I and is swung back into the position shown in Fig. 2, whereby the half-bearing J is deprived of its support on the portion j , and is, through the weight of the eccentric-rod B, thrown out of its normal position and away from the wrist-pin c^4 of the center lever, C. The eccentric-rod B, having lost its support and connection with the wrist-pin c^4 , drops down to the bottom k of the guide-stand K, and the engine, having its valve motion arrested and being without steam-supply, will stop. In order to reconnect the center lever, C, to the eccentric-rod B, the supply steam is first cut off in the ordinary way. The eccentric-rod is then lifted up to the wrist pin c^4 , the half-bearing J is closed up upon it, pushing first the lever b back, and when in its normal position allowing the shoulder b^2 to move over the end portion, j , and lock it to the eccentric-rod. The engine is now ready to be started.

Heretofore a person caught in the machinery was helplessly lost before the engineer could be informed so as to stop his engine in time, and would be horribly mangled before help could be offered. With the aid of my invention the machinery is stopped as soon as the person is caught therein and the electric

switch-button operated, and the result will be, generally, only some slight injury to the body or wearing apparel.

45

It is readily seen that my invention can be applied to the eccentric-rods of steam-engines other than that of the Corliss, which latter I have selected for the illustration of my invention only for the reason of the preference 50 which is shown for it among the owners of large mills and shops.

When the center lever, C, of a Corliss engine is turned up instead of down, as shown in the drawings, the box G may be fastened to the cylinder A, so that the motion of the spring-bolt toward the lever b may be downward.

What I claim as my invention is—

1. In an electric stop-motion for steam-engines, the combination, with an eccentric-rod 60 having a divided wrist-pin bearing and a locking and trip lever for said bearing, of an electric trip mechanism, F, whereby the trip-lever is operated and the eccentric-rod disconnected from the valve, substantially as and for the 65 purpose described.

2. The combination of the magnet H, armature h' , check-bolt h , having lug h^2 , spring-bolt I, and an eccentric-rod having half-bearings J b^6 , and locking-lever b , substantially as and 70 for the purpose described.

3. In a steam-engine, the combination of an electric trip mechanism and a separable eccentric or valve rod connection, whereby the steam-engine is stopped by a switch of said 75 trip mechanism and without shutting off the steam-connection with the boiler, substantially as and for the purpose described.

In testimony whereof I affix my signature in presence of two witnesses.

ROBERT EXLEY.
